UNITED STATES PATENT OFFICE

2,476,162

HIGH-FREQUENCY APPARATUS

Leland E. Thompson, Merchantville, N. J., assignor to Radio Corporation of America, a corporation of Delaware

Original application February 6, 1945, Serial No. 576,453. Divided and this application March 15, 1946, Serial No. 654,553

4 Claims. (Cl. 332—25)

1

This is a division of my co-pending application Serial Number 576,453, filed February 6, 1945, entitled Radio relaying.

In my copending parent application referred to, I have described an ultra short wave radio relaying system making use of an ultra short wave oscillation generator. This oscillation generator is of the type making use of a cavity resonator having a gap, oscillations being produced in the resonator by an electron discharge system including a negatively charged anode, a positively charged grid and a cathode.

An object of my present invention is to provide improved circuit arrangements for frequency modulating the output of such a high frequency oscillation generator. A further object is to provide improved circuits for automatically frequency controlling the same. Other objects, advantages and features will appear with the more detailed description of my present invention.

In the accompanying drawings—

Figure 1 illustrates schematically a transmitting terminal for an ultra high frequency relay system. The terminal makes use of a high quality voice channel having, as indicated, an upper frequency of 10,000 cycles although if desired this may be raised to 15,000 cycles and several other signaling channels which are transmitted to a common amplifier as side bands of suitable sub-carriers. All of the signals are combined, pre-emphasized in a suitable network and used to frequency modulate a common sub-carrier having, as illustrated, a mean frequency of one megacycle. The latter, in turn, is used to frequency modulate a transmitted carrier having a mean frequency of 3,000 megacycles.

Figure 2 is a block diagram of a relay station for use with the transmitting terminal of Fig. 1. It will be noted that the received doubly modulated waves are converted to a suitable intermediate frequency, amplified, and then subjected to a single frequency demodulation. The waves resulting from this single frequency demodulation are then used in part for purposes of automatic frequency control of the local beating oscillator and to frequency modulate a new locally generated carrier.

Figure 3 is a schematic showing of a high frequency oscillator and circuits therefor for utilizing

2

ing the frequency modulated sub-carrier produced by the apparatus of Figure 1 for frequency modulating a very high frequency carrier which is to be radiated directly to a receiving terminal or to a relay station such as illustrated in Figure 2.

Figures 4 and 5 are different cross sectional shapes which the cavity resonators may take for use in Figures 3 and 6, and Figure 6 is a more detailed schematic diagram of the first local oscillator and converter employed at a relaying point such as Figure 2 or at the terminal receiver such as shown in my parent application. Figure 6 also illustrates circuits for automatically frequency controlling the first beating oscillator.

In Figure 1, several independent signaling channels are combined and modulate the waves radiated from the transmitting antenna TA to the receiving antenna RA200 of the relay station of Figure 2. The waves received at the relay station are heterodyned, amplified, detected and used to modulate a different carrier frequency wave. The latter is radiated over the relay transmitting antenna TA214 to the receiving antenna of a terminal station.

Turning more specifically to Figure 1, the signal channels are designated by the letters A to F, inclusive. These channels are combined in resistor 23 and fed through transformer 24 and pre-emphasizing network PN in order to oppositely frequency modulate oscillators 25 and 102.

Oscillator 25 may operate, by way of example, at an unmodulated frequency at 10 megacycles and oscillator 102, for example, at an unmodulated frequency of 11 megacycles. The outputs of the two oscillators 25 and 102 are combined in the converter 100 as a result of which the frequency modulation appearing in the peak frequency output of converter 100 is equal to the sum of the deviations of the oscillators 25 and 102 when they are caused to separate in frequency.

The deviation ratio of the modulated waves appearing in the output circuit of the second frequency modulated oscillator 104 is unity or more, as desired, as a result of which the waves radiated over the transmitting antenna TA have for maximum deviation, a frequency of 3000 megacycles plus and minus 1.0 megacycles. A larger deviation ratio may be used, in which case

the radiated waves would be, for example, 3000 megacycles plus and minus 2, 3, or more megacycles when fully modulated.

The waves radiated from the transmitting antenna TA of Figure 1 may be received directly by receiving apparatus as shown in my parent application. Ordinarily, however, such waves would be radiated to the receiving terminal by way of one or more relaying points, such as illustrated in Figure 2. The waves would be received at the relay point at one frequency and re-transmitted to the next point in the system at some different frequency so as to avoid feedback or "singing" at the relay station.

In the relaying system illustrated in Figure 2, the waves are picked up or received on a receiving antenna RA200. The received waves are beat down in frequency in a converter circuit 202 with waves from a local beating oscillator 204. The intermediate frequency produced may be 30 megacycles plus and minus 1.0 megacycles. The waves of intermediate frequency are amplified in an intermediate frequency amplifier 206 and then fed to a discriminator detector 208.

The action of the discriminator detector is such as to produce a wave of one megacycle plus and minus 170 kilocycles corresponding to the output of the converter 100 of Figure 1. This wave is limited and amplified in appropriate apparatus 210 and then used to frequency modulate oscillator 212 whose unmodulated frequency may be 3010 megacycles.

By adjusting the amplitude of the output of amplifier 210 the waves radiated over the transmitting antenna TA214 of the relay point of Figure 2 may be made 3010 megacycles plus and minus 1.0 megacycles.

Also it is to be noted that all of the channels need not be voice channels, but, if desired, some of them may be telegraph channels, some voice and some of other types, such as facsimile and teletype channels. Thus, as a possible alternative channel A may be replaced by twelve telegraph channels, the separate telegraph carrier tones of which may occupy the band from 465 to 2295 cycles, each tone channel having a width of 170 cycles. Thus, the first telegraph channel may be designed for a tone carrier of 465 cycles with a signaling width of plus and minus 85 cycles, the second tone channel may use a tone carrier of 595 cycles with a cycle width of plus and minus 85 cycles, etc.

In addition to channels A-F inclusive, of Figure 1, a service channel SC may be provided. The output of the service channel pick-up microphone may be amplified by the service channel amplifier SCA and switched directly, by means of switch SCS, to frequency modulate oscillator 104. Preferably, amplifier SCA passes a band of approximately 0-5000 cycles and the amplitude of the modulating voltages is adjusted so as to produce, for example, a maximum swing of $\pm 15,000$ cycles in the output of oscillator 104.

As indicated in Figure 2 the service channel band may be filtered out by filter SCF and taken from line SCL for use in earphones, or the output of line SCL may be fed by patch cords to the service line input SLI to modulate oscillator 212.

In Figure 3 there is shown a form of high frequency oscillation generator which is used at 104 in Figure 1 and at 212 in Figure 2. Figure 3 also illustrates circuits especially adapted for producing frequency modulation of the high frequency oscillator 104.

The oscillation generator of Figure 3 comprises

an evacuated container 600 which may be of glass or metal, within which are contained a heated cathode 601, a screen electrode diagrammatically illustrated in section at 603, a cavity resonator 604, and a disc-like metallic anode or electron receiving plate 605. The cathode 601 is externally grounded at 602. The cavity resonator 604 is made of metal and consists of a metallic cylinder 606 having metal bases 607, 608. Mechanically and electrically fixed to the bases are the internally protruding sleeves or tubes 609, 610 separated so as to have between them a gap 611. The tube 606, cavity resonator 604, sleeves 609, 610 and plate 605 are shown in cross section.

Actually, the cavity resonator may have different dimensions and be proportioned differently than as shown in Figure 3. The distance between the bases 607, 608 may be equal to or less than the internal diameter of the cylinder 606, as shown diagrammatically in cross-section in Figure 4. Also, the bases may be dished in and the cavity resonator have the toroidal or doughnut shape shown in cross-section in Figure 5.

The anode 605 of Figure 3 is maintained at a negative potential of the order of -150 volts with respect to ground by means of lead 612 connected through resistors 613 and 614 to a suitable source of potential 615 by-passed to ground by means of the by-pass condenser 616. The cavity resonator 604, together with the grid 603 connected thereto, is maintained at positive potential of the order of +300 volts, for example, with respect to ground by means of lead 617 connected to a suitable source of potential 618 by-passed by condenser 619.

As a result of the foregoing construction, electrons emitted from the cathode 601 are attracted to and pass through the hollow portion of tubes 609 across gap 611 and through tube 610. The electrons then approach the negatively charged anode 605 only to be repelled and attracted back across the gap 611. In this way, the cavity resonator 604 is excited so that high frequency waves are set up therein at a frequency determined, in the main, by the cubical content of the cavity resonator 604. The frequency of operation is also dependent, to a certain extent, upon the voltages applied to the various oscillator elements.

Output energy is taken from resonator 604 by means of conductor 620 coupled by means of the inductive loop 621 to the space within the cavity resonator 604. Conductor 620 is suitably shielded by means of the externally grounded metallic coaxial conductors 621A, 622. The high frequency conductor 620 leads to and excites the transmitting antenna TA of Figure 1 or the relay transmitting antenna TA-214 of Figure 2.

When the oscillator in Figure 3 is used in the transmitting arrangement of Figure 1, it is modulated by the output of the converter or mixer 100 of Figure 1. The output of mixer 100 is fed through conductor 101a to the anode circuit of anode 605 of Figure 3. In the case of the transmitter of Figure 1 conductor 101a will carry a frequency modulated wave of one megacycle having a maximum frequency deviation of ± 170 kilocycles, according to the example chosen.

The waves in conductor 101a, referring to Figure 3, are resonated in the parallel tuned circuit 623 comprising coil 624, to which conductor 101a is variably tapped at tapping point 625, and condenser 626. The tuned circuit 623 is broadened by the use of a loading resistor 627 connected in shunt to the circuit. By means of variable con-

denser 628, the frequency modulated waves appearing in line 101a are applied, in controllable amounts, to the plate 605. As a consequence, the output of the oscillator of Figure 3, appearing in lead 620, is frequency modulated to an extent which may be controlled primarily by adjustment of condenser 628, and secondarily by adjustment of tap 625.

Since the negative voltage applied to the lead 612 is fed through resistors 613, 614 which may, by way of example, be 22,000 and 180,000 ohms in value, respectively, leakage of the waves appearing in circuit 623 to ground through lead 612 is effectively prevented.

For monitoring and adjustment purposes, a portion of the high frequency waves fed through condenser 628 to the plate 605 may be shunted through high frequency by-passing condenser 629 to switch 630. The latter, in its upper contact position 631 feeds the rectifier 632 to the output of which is connected a suitable meter 633. The rectified output of rectifier 632 will indicate the voltage applied to plate 605 and will be a measure of the frequency deviation in the oscillations generated by the oscillation generator and fed to the output transmission line 620.

The service channel is fed through switch SCS of Figure 3, which corresponds to switch SCS of Figure 1, across a potentiometer 634. For modulating the high frequency oscillator of Figure 3 with the service channel voltages, the latter are fed through tap 635, audio frequency by-pass condenser 636, across resistor 614 and through resistor 613 and lead 612 to the anode 605 of the oscillation generator. By throwing switch 630 to the lower position 637, the extent of the frequency modulation produced by the service channel may then be measured by noting the reading on meter M which will then be actuated by rectified service channel voltages. For aurally monitoring the service channel an amplifier 638 and earphones 639 are provided, as indicated.

It is again repeated that all values of frequencies, resistances, voltages, etc. are given as illustrative or typical only and, therefore, it is to be clearly understood that all inventions described herein with reference to all figures of the drawings are not to be restricted to such values.

In Figure 3 the filament heating voltage source for cathode 601 is illustrated to be a battery but this battery may be replaced by a transformer supplying suitable alternating voltages to the filament for heating the cathode to an electron emissive condition. Also, the sources 618 and 615 for the cavity and plate may be replaced by potentiometers supplied with rectified commercial 60 cycle current. Such alternating currents for exciting the filament and the ripple in the rectified voltages may produce 60 cycle and 120 cycle frequency modulation of the output of the oscillator of Figure 3. This hum will therefore appear in the service channel. It will not appear, however, in the high quality channel A or in the channels B to F inclusive, since such low frequency modulation is effectively filtered out by the selectivity of the subcarrier circuits in the receiver.

This filtering action follows since there is a substantial separation in frequency between the first significant side bands produced by the subcarrier in the output of the oscillator of Fig. 3 and the side bands produced by the low frequency power modulation. Therefore the power supply hum and mechanical vibration modulates the carrier, but not the subcarrier. The signal channels A to F receive only the modulation of the sub-

carrier. The low frequency power modulation is produced by the 60 cycle heating supply or harmonics of 60 cycles representing ripple in the rectified power supply. This undesired low frequency modulation may also be produced by undesired mechanical vibration.

It is to be noted that oscillators of the type shown in Figure 3 are peculiarly susceptible to this low frequency type of frequency modulation due to mechanical vibration or the use of imperfectly filtered rectified power or due to the use of alternating current operation of the cathodes. It is one feature of my invention that the type of modulated oscillator shown in Figure 3, which is particularly susceptible to frequency modulation due to imperfectly filtered, rectified power or to the use of alternating current on the cathode, can be used without disturbing the signal.

Incidentally if it is desired to transmit a single channel, for example high quality channel A alone, amplifier 22 of Fig. 1 would be switched out of circuit so that across resistor 23, only voltage from channel A or amplifier 8 would be set up. Channel A would be adjusted so as to produce a full deviation of plus and minus 170 kilocycles in the output of converter 100. This simplex high quality signal could be radiated directly to receiving apparatus or relayed thereto through the apparatus of Figure 2.

The frequency of operation of the oscillator of Figure 3 is determined by the dimensions of resonator 604 and may be controlled by providing suitable externally operated means for warping of the sides of the cavity resonator 604 so as to change its internal volume. Also, the frequency may further be controlled by adjustment of the voltages applied to the electrodes of the oscillator.

Figure 6 illustrates in greater detail the beating oscillator-converter apparatus designated schematically at 202 and 204 in Figure 2. That is, the receiving antenna RA-200 of Figure 2 is connected to the transmission line 700 of Figure 6. Line 700 is provided with an externally 45 metallic shield 702, grounded at 704. Also, transmission line 700 is terminated by an inductive loop 705, thereby establishing coupling within the cavity resonator 706. If desired, transmission line 700, 702 may be replaced by a wave chute 50 or guide.

The cavity resonator 706 is of metal and cylindrical in shape. Extending within the resonator 706 and connected to one of its bases is cylindrical line section 790 whose base 791 is adjacent 55 and spaced from the metal circular base 792 carried by metal bellows 711. The line section 790 is tuned by means of this cylindrical metallic bellows 711 having, as indicated, springy corrugated side walls. By means of the bolt 713 and nut 715, the capacity between plates 791 and 792 is adjusted as is also the volume or internal cubical content of the resonator. Preferably the line section 790 is approximately one quarter wave length long—here about $\frac{3}{4}$ of one inch. 60 This line section is tuned by adjustment of plate 792 to the frequency of the waves received and fed in at 705. A crystal detector 708 is mounted as shown with one terminal 795 in electrical contact with 706 and its other terminal 796 protruding through opening 797 in the cylindrical line section 790. Terminal 796 is connected to conductor or line 710. As a result, the crystal detector rectifies the waves fed in at 705 and 718 65 and feeds the resulting difference frequency of 75 about 30 mc. into line 710.

The cavity resonator 106 is also supplied with high frequency oscillations by means of a capacity end plate 118 fixed to an exposed section of transmission line 720 protruding within the resonator. The line 720 is excited by an automatically frequency controlled high frequency oscillator operating in the neighborhood of either 3030 megacycles or 2070 megacycles. The oscillator will be described more fully later.

The beat frequency is fed through line 710 shielded by the external conductor 712 to the primary 716 of a transformer whose secondary coil 726 is tuned by condenser 728. The output of the tuned circuit 726, 728 is fed through line 132 to the first stage of the intermediate frequency amplifiers and limiters 206 of Figure 2.

The high frequency oscillator 138 of Figure 6 operating in the neighborhood of 2070 megacycles or 3030 megacycles is similar in all essential respects to the high frequency oscillator 600 of Figure 3.

In Figure 6, the oscillator comprises an evacuated container 738, a cathode, 734, grounded at 736, a negatively biased plate 756, a positively charged cavity resonator 742 and a grid 144 connected to the resonator. The resonator 742, shown in cross section, is cylindrical in shape and is made of metal. The resonator has metallic bases 752, 754 which are perforated and to which are attached the hollow metallic tubes 746, 750. The tubes 746, 750 are separated at an intermediate point so as to provide a gap 748. In a way similar to that explained in connection with Figure 3, oscillations are set up in the cavity resonator 742 of Figure 1 and wave output is derived from the inductive loop 740 coupled to the space within the cavity resonator 742.

The external surface of the cavity resonator 106 is grounded at 104 as indicated.

By properly choosing the dimensions of the cavity resonator 742 and by appropriate adjustment of the voltages on the elements of the oscillator, oscillation at a desired frequency may be had. As before indicated, by suitable external means the shape of resonator 742 may be warped so as to change its cubical content and, hence, its frequency of operation. Or, if desired, a metallic bellows adjustment, such as that provided for the cavity resonator 706 may be provided for 742, but in this case, of course, the container 738 should be hermetically sealed to resonator 742 so that a portion of its external surface containing and otherwise supporting the metallic bellows structure would be exposed for external adjustment.

The output appearing in the tuned circuit 726, 728 would be, for the example chosen, a wave as indicated in Figure 2 having a mean frequency of 30 megacycles and maximum frequency deviation of ± 1.0 megacycles. This wave is fed to the intermediate frequency amplifying, limiting and discriminator detector stages.

The discriminator detector of Fig. 2 is also diagrammatically illustrated at 208 in Figure 6 across the output terminals of which are connected resistors 182, 184, which, as will be explained more fully later, provide automatic frequency controlling voltages. These voltages may then be used to control the frequency of oscillator 138 so as to maintain the beat frequency waves within the pass band of intermediate frequency amplifying and limiting stages 206 of Figure 2.

The frequency controlling circuit for the oscillator 138, from which the automatic frequency controlling voltages are derived, is illustrated

schematically in Figure 6 in connection with vacuum tube 760. More specifically, a source of voltage 765 is connected across the leads or terminals 776, 778 and these terminals are connected to a potentiometer 774. By properly adjusting the tap 772 on potentiometer 774, and by proper choice of values for other circuit elements, the current flow through, or the conductivity of tube 760, having the anode 762, grid 764, and the cathode 768, may be controlled so that the voltage applied through lead 758 upon the plate 756 is of a desired value, such as, for example, -150 volts. As indicated, the plate circuit for tube 760 is returned to ground through a resistor 761 shunted by condenser 792 and through the ground connection 763 to the source of potentials 765. It should, therefore, be clear that the automatic frequency controlling voltages appearing across resistors 182 and 184 will vary the current flow through the tube 760 and hence its effective resistance. Consequently, the voltage in lead 758 will vary in such a way as to control the oscillator in that direction which will bring the beat frequencies appearing in 726, 728 back to the desired intermediate frequency pass band of the IFA system 206 of Figure 2.

I claim:

1. High frequency apparatus comprising a cavity resonator having a gap, a negatively charged anode located on one side of said gap, an electron emitting cathode on the other side of said gap, a circuit for maintaining said resonator at a positive potential with respect to said cathode whereby oscillations are produced by electron flow across said gap, a tuned circuit connected to said anode, apparatus for producing high frequency waves in said tuned circuit whereby the oscillations produced in said cavity resonator are frequency modulated in accordance with the high frequency oscillations in said tuned circuit, and apparatus for adjusting the coupling of said tuned circuit to said anode in order to control the amount of frequency modulation in the oscillations within said cavity resonator.

2. Apparatus as claimed in the preceding claim, characterized by the fact that said adjustable coupling consists of a variable condenser.

3. High frequency apparatus comprising a cavity resonator having a gap, a negatively charged anode located on one side of said gap, an electron emitting cathode on the other side of said gap, a circuit for maintaining said resonator at a positive potential with respect to said cathode whereby oscillations are produced by electron flow across said gap, a tuned circuit connected to said anode through a variable impedance, means coupled to said tuned circuit at a location effectively intermediate its ends for supplying frequency modulated signals thereto, to thereby excite said tuned circuit and cause the oscillations produced in said cavity resonator to be frequency modulated in accordance with the high frequency oscillations in said tuned circuit, said variable impedance enabling an adjustment of the coupling of said tuned circuit to said anode in order to control the amount of frequency modulation in the oscillations within said cavity resonator.

4. High frequency apparatus comprising a metallic cavity resonator having a gap, cathode and electron repeller electrodes on opposite sides of said gap, a source of unidirectional potential connected to said resonator, a source of unidirectional potential connected to said repeller electrode through a resistor, said sources maintaining

said resonator and repeller electrode at potentials of different polarities relative to said cathode, a parallel tuned circuit of inductance and capacitance connected between said repeller electrode and said cathode, a loading resistor in shunt to said tuned circuit, a source of frequency modulated waves adjustably connected to a point on the inductance of said tuned circuit, and an adjustable element in circuit with said tuned circuit for varying the degree of coupling of said tuned circuit to said repeller electrode, and an output circuit coupled to said resonator, whereby the extent of frequency modulation produced in said resonator is controlled by both adjustable connections.
